UNITED STATES PATENT OFFICE

AUGUSTE F. JACQUEMIN, OF KENNEBUNK, MAINE, ASSIGNOR TO ROBERS FIBRE COMPANY, OF KENNEBUNK, MAINE, A CORPORATION OF MAINE

COUNTER MOLDING MACHINE

Application filed June 25, 1929. Serial No. 373,602.

This invention relates to the manufacture of molded counter stiffeners, more commonly called "counters".

A counter usually is made of fibre board or leather and includes a main body shaped to fit around the sides and back of the heel and an inturned flange which lies under the bottom of the heel. The usual commercial counter molding machines include a center mold similar in shape to the heel portion of a shoe last and side molds movable toward and from the center mold and cooperating with it to shape the main body of the counter. While the counter is gripped between and being shaped by these molds, a wiper slides down over the front face of the center mold and turns over the flange and irons it down.

There is considerable tendency for the flange to spring back after it has been released from the molds and thus to change its relationship to the main body of the counter. This impairs to some degree the fit of the counter on the shoe last and is objectionable for this reason. Attempts to overcome this difficulty by applying additional pressure on the wiper are only partially successful and the increased pressure tends to cause the wiper to shear the flange off the main body of the counter and thus to ruin it.

The present invention deals especially with this problem and aims to devise a simple and thoroughly satisfactory solution for it.

The nature of the invention will be readily understood from the following description when read in connection with the accompanying drawings, and the novel features will be particularly pointed out in the appended claims.

In the drawings,

Fig. 1 is a side elevation, partly in vertical section, showing part of a counter molding machine equipped with mechanism embodying this invention;

Fig. 2 is a perspective view of a molded counter;

Fig. 3 is a front elevation of the mechanism shown in Fig. 1, certain parts, however, being omitted;

Fig. 4 is a vertical sectional view on substantially the line 4—4, Fig. 3;

Fig. 5 is a bottom view of the slides shown in Fig. 3 and the parts carried thereby; and Figs. 6 and 7 are sectional views showing a modification.

The mechanism provided by this invention can be used on practically any of the commercial counter molding machines. For purposes of disclosure the invention has been illustrated as applied to the counter molding machine shown and described in my prior Patent No. 1,832,259. This machine, in common with other counter molding machines, such as the Stewart and Young machines, includes a center mold 2 and two cooperating side molds 3—3, Fig. 3. The side molds are arranged to swing laterally toward and from the center mold, and the latter mold has both an up and down movement relatively to the side molds, and also a movement backward and forward into and out of the plane of the side molds in order to facilitate the removal of the molded counter from the center mold. In the machine shown in the patent above designated guide pieces 4—4 are secured to the frame of the machine at the front thereof and cooperate with the frame to form vertical guideways in which the wiper slides. The sliding movement is given to the wiper by a cam operated mechanism including a lever 5, Fig. 1, and a link 6. For a more complete understanding of the general organization the machine and the features just mentioned, reference should be made to my prior patent above designated.

When the counter blank is brought to the counter molding machine it is slightly damp or in "temper", the preliminary shaping operations have been performed on it, and usually it has been "rolled". This rolling operation concaves the counter blank and corrugates the margin which later will be turned over to form the flange. The blank so prepared is bent into a horseshoe shape and placed between the center and side molds while they are open, the margin of the blank which is to be turned over to form the flange being left projecting in front of the faces of the molds. The molds then close, thus gripping the blank securely and shaping it, and while the blank is so held the wiper slides

down over the front faces of the molds and turns over the flange.

The mechanism provided by this invention comprises not only a wiper for turning over the flange and ironing it down, but also additional means, consisting of a roller, for pressing the flange firmly against the front face of the center mold. In the machine shown the usual wiper plate is replaced by a slide 7 having gears or lugs 8-8 integral with it and to which the link 6 of the usual mechanism for operating the wiper is connected, so that this slide is reciprocated across the face of the molds in substantially the same manner as the ordinary wiper plate. Immediately below the slide 7 is a second or supplemental slide 10 which travels in the same guideways as the slide 7. This second slide 10 has two arms 12-12 integral with it which lie in front of a part of the slide 7 and are secured to it by bolts 13-13. This slide thus has, roughly speaking, a U-shape. A wiper 14 is set into a recess formed in the inner or rearward side of the slide 10, as clearly shown in Fig. 5. In order to adjust the wiper relatively to the slide 10, three thrust screws 15 are threaded through the horizontal part of the slide and bear against the wiper 14, while two bolts 16-16, which extend loosely through the slide 10, are threaded into the wiper and serve to draw it against the inner ends of the thrust screws or bolts 15. This arrangement permits an accurate adjustment of the inner face of the wiper relatively to the outer or front face of the center mold 2.

The wiper acts on the projecting margin or flange *a*, Figs. 2 and 3, of the counter just as do the wipers in the ordinary counter molding machines, serving to turn the flange over upon the outer face of the center mold and iron it against said face. In the construction shown, however, the wiper 14 is much shorter than in the ordinary counter molding machine.

The roll 18 which also acts on the flange of the counter is provided with gudgeon or axle members rotatably mounted in two parallel arms 19-19, both pivoted to the upper end of the slide 7 at 20-20, Fig. 3. The slide 7 is slotted, as shown at 21, to receive the roll. In order to adjust the pressure exerted by the roll on the flange, bolts 30-30 extend through the lower ends of the arms 19-19 and are threaded into the slide 7 so that by turning them in or out the roll 18 can be adjusted toward or from the front face of the center mold 2.

The operation of the mechanism will be clearly understood from the foregoing description. It should be noted that as the slides 7 and 10 are moved downwardly, the wiper 14 first comes in contact with the projecting flange of the counter, turns this flange over and presses it against the front face of

the center mold 2 exactly as in prior machines, but that this wiper is immediately followed by the roll 18 which applies additional pressure to the flange, forcing it all the more firmly against the front face of the center mold. The action of the roll, however, is quite different from that of the wiper since it does not have the rubbing effect which is characteristic of the wiper. Usually the molds are heated, and the wiper also is sometimes heated, as in prior machines, the heat serving to set the fibre more definitely in the desired shape and to reduce the tendency of the fibre to spring back after the counter is released from the molds.

It should be noted that in this machine the roll 18 and wiper 14 are supported independently of each other and are independently adjustable. Consequently, the pressure applied by either of these members to the flange of the counter can be adjusted independently of the other. This is an important practical advantage. It is entirely feasible, and usually preferable, to use more pressure on the roll 18 than on the wiper 14 due to the fact that the roll follows the wiper, and the further fact that the rolling action does not tend to shear the flange off the body of the counter as does the wiping action. At the same time the heavier pressure of the roll and the ironing action of the wiper cooperate to set the flange firmly in its desired position so that the tendency for the flange to spring back is substantially eliminated. This arrangement of the two members which act on the flange so that their pressure can be independently adjusted is also valuable in cases where these members are of such a nature that they exert substantially the same action on the flange, as well as in those cases where their action is quite different.

The mechanism so far described is designed for use in molding counters in which the flange is flat and lies in a single plane. In the molding of such counters the surface of the roll 18 is substantially a true cylinder. It rolls freely in its bearings and is revolved by the friction of the material on which it bears. There is some demand, however, for a counter having a depressed or concaved flange. In order to mold the flange in this form, the front face of the center mold is recessed or concaved, as indicated in Figs. 6 and 7, where the front face *c* of the mold 2' is so shown. The roll 18' carries a boss *d* which is complementary in cross-sectional form to the face *c* so that after the wiper has turned over the flange in the usual manner, the boss on the roll will then press the turned over flange firmly into the recessed portion of the face of the center mold and set it in this position.

It will be clear that when a roll of this construction is used the boss must coincide at each cycle of the machine with the cavity in

the roll, and this requires that the roll be driven positively. For this purpose a gear 22 is secured fast to the roll and meshes with another gear 23 which runs in contact with a stationary rack 24. The rack is suspended from a bracket 25, Fig. 1, and is held in mesh with the gear 23 by a small bracket 26, Figs. 1 and 5, bolted to one of the arms 19. Suitable adjustment of the rack relatively to the gear 23 is afforded by a shoe or wear piece 27 held in the bracket 26 and backed up by an adjusting screw 28. This mechanism keeps the roll properly timed to register with the depression in the center mold.

15 The flange of a counter molded by the mechanism shown in Figs. 6 and 7 instead of being flat and lying in a single plane, as in Fig. 2, extends inwardly with reference to said plane.

20 The invention provides a mechanism which substantially eliminates the spring back of the flange, and which has the sturdy and rugged characteristics necessary in counter molding machines. It also supplies a single 25 and efficient machine for molding counters with depressed flanges.

25 While I have herein shown and described a typical embodiment of my invention, it will be understood that the invention may be embodied in other forms without departing from the spirit or scope thereof.

Having thus described my invention, what I desire to claim as new is:

30 1. In a machine of the character described, the combination of cooperating molds for molding a counter, a wiper for acting on the flange of a counter held by said molds, a roll for acting on said flange, means for reciprocating said wiper and roll on said flange, and means for positively rotating said roll as it is moved across said flange.

35 2. In a machine of the character described, the combination of cooperating molds for molding a counter, a wiper for acting on the flange of a counter held by said molds, a roll for acting on said flange, means for reciprocating said wiper and roll on said flange, independent supports for said wiper and roll, and means for positively rotating said roll on said flange.

40 3. In a machine of the character described, the combination of cooperating molds for molding a counter, a wiper for acting on the flange of a counter held by said molds, a roll for acting on said flange, means for moving said roll and wiper to transfer their points of operation along the flange, means for positively rotating said roll as it is moved across said flange and means whereby the pressure 45 of said roll on the flange may be adjusted independently of that of the wiper.

45 4. In a machine of the character described, the combination of cooperating molds for molding a counter, a wiper for acting on the flange of a counter held by said molds, a roll

for acting on said flange, means for moving said roll and wiper to transfer their points of operation along the flange, and means adjustable to regulate the pressure of said wiper and roll on the flange independently of each other.

5. In a counter molding machine, the combination of a center mold, side molds cooperating therewith to mold a counter, a wiper for turning over the flange of the counter, a roll for acting on said flange to press it down, slides on which said wiper and roll, respectively, are mounted, guideways in which said slides travel, and means for reciprocating said slides.

6. In a counter molding machine, the combination of a center mold, side molds cooperating therewith to mold a counter, a wiper for turning over the flange of the counter, a roll for acting on said flange to press it down, slides on which said wiper and roll, respectively, are mounted, guideways in which said slides travel, and means common to both of said slides for reciprocating them.

7. A claim according to preceding claim 5 characterized by means for positively rotating the roll during its movement along the flange of the counter.

8. In a counter molding machine, the combination of a center mold having a recessed tread face, side molds cooperating with said center mold to mold a counter, means slideable across the tread face of said center mold for wiping the flange of the counter over said face, and additional means having a rolling engagement with said flange for pressing the flange firmly against the recessed portion of said face.

9. In a counter molding machine, the combination of a center mold having a recessed tread face, side molds cooperating with said center mold to mold a counter, means slideable across the tread face of said center mold for wiping the flange of the counter over said face, additional means for pressing said flange against the recessed portion of said face, and means adjustable to regulate the pressure exerted on said flange by said pressing and wiping means independently of each other.

10. In a counter molding machine, the combination of a center mold having a recessed tread face, side molds cooperating with said center mold to mold a counter, means slideable across the tread face of said center mold for wiping the flange of the counter over said face, additional means for rolling the flange against the recessed portion of said face, and means for supporting said wiping and rolling means independently of each other.

11. In a counter molding machine, the combination of a center mold, side molds cooperating therewith to mold a counter, a slide, means supporting said slide for recip-

- roating movement relatively to said molds, a wiper connected with said slide for acting on the flange of a counter gripped by said molds to press said flange against the face of the center mold, an additional device connected with said slide for acting on said flange to press it against said face, and means adjustable to vary the pressures exerted by said wiper and said device on the flange of the counter independently of each other.
12. In a counter molding machine, the combination of a center mold, side molds co-operating therewith to mold a counter, a slide, means supporting said slide for reciprocating movement relatively to said molds; a wiper connected with said slide for acting on the flange of a counter gripped by said molds to press said flange against the face of the center mold, a roll carried by said slide and arranged to act on the flange of the counter simultaneously with said wiper, and means adjustable to vary the pressure exerted by said roll and wiper on the flange of the counter independently of each other.
13. In a counter molding machine, the combination of a center mold, side molds co-operating therewith to mold a counter, a slide, a machine frame supporting said molds, guides carried by said machine frame for supporting said slide for reciprocating movement over the faces of said molds, two members connected with said slide to be moved thereby and both arranged to act simultaneously on the flange of a counter while it is held between the molds, and means adjustable to vary the pressure exerted by said members on said flange independently of each other.
14. In a counter molding machine, the combination of a center mold, side molds co-operating therewith to mold a counter, a slide, a machine frame supporting said molds, guide members carried by said machine frame for supporting said slide for reciprocating movement over the faces of said molds, a second slide guided by said members and connected with said first slide to move therewith, a wiper carried by said second slide, a roll mounted on said first slide, both said wiper and roll being arranged to act on the flange of a counter held between said molds to press said flange against the face of said center mold, and means adjustable to vary the pressure exerted by said roll on said flange.
